United States Patent Office.

MARTIN L. WYMAN, OF MELROSE, ASSIGNOR TO OTIS TUFTS, OF BOSTON, MASSACHUSETTS.

Letters Patent No. 100,832, dated March 15, 1870.

IMPROVED ELEVATOR.

The Schedule referred to in these Letters Patent and making part of the same.

To all whom it may concern:

Be it known that I, MARTIN L. WYMAN, of Melrose, in the county of Middlesex, and State of Massachusetts, have invented an Improvement in Elevators; and I do hereby declare that the following, taken in connection with the drawings which accompany and form part of this specification, is a description of my invention sufficient to enable those skilled in the art to practice it.

In that class of elevators in which the car or platform is raised and lowered with passengers or freight by the employment of a special engine operating through suitable instrumentalities little regard has heretofore been paid to economy in the expenditure of steam employed to give motion to the car. The engine-cylinder or cylinders have to be made large enough to start and lift from a state of rest the greatest load for which the elevator is designed, and with cold cylinders, which will, of course, condense a considerable percentage of the steam at the start, and in the first few strokes of the pistons the steam should be allowed to follow throughout the length of the strokes, or a large portion thereof. But when the cylinders are heated, so that very much less steam is required by reason of lessened condensation, then it is simply a waste of steam to allow it to follow the pistons their entire stroke, and it should be cut off at some suitable point in the stroke, and it is desirable that such cutting off of the steam should be accomplished automatically after the car has moved a short distance from each start. Heretofore the steam has been allowed to follow the full or a large portion of the stroke of the pistons of engines whose sole duty was to move the car or platform of an elevator, not only at the starting of the car, but during all the time that the pistons, and, consequently, the car or platform, were in motion, as the attendant or conductor is necessarily stationed on the platform, or in the car, the motion of which renders it impossible for him to set the engine-valves with more accuracy than to fully open or to fully close them by operating on the pull within his reach, and past which the car moves.

Now, my invention consists in combining with an elevator, the car or platform of which is moved by a special engine, instrumentalities which automatically operate upon the engine-valve or valves, to cause it or them to cut off steam at some suitable portion of the stroke of the piston or pistons, after the elevator-car or platform has been put in motion, by receiving steam throughout or nearly throughout the stroke of the piston or pistons, my invention operating to give the engine a large amount of steam when starting the elevator, and to cut off or automatically lessen the supply of steam to the engine after each start.

In the drawings, by which I illustrate an embodi-

ment of my invention, I merely show the simplest but not the best way of connecting the elevator-car to the drum, worked by the engine to wind or unwind the suspensory of the car, as improvement in that direction forms no part of my present invention; and of the engine, I show only enough to illustrate the invention under consideration, leaving out parts the connection, construction, and method of operation of which are known to all competent engineers.

In the drawings—

Figure 1 shows, in vertical sectional elevation, an apparatus embodying my invention;

Figures 2 and 3 being partial similar views, showing the apparatus for working the engine-valves in different positions.

As elevator-cars have to start and stop almost instantly, it is not desirable, in special engines for working them, to provide the engines with heavy or large fly-wheels; but to enable them to start without regard to where the engine is stopped, it is necessary, as in locomotives, to make use of two cylinders connected to a common crank-shaft by cranks set ninety degrees, or thereabouts, of angular distance from each other, and it is also necessary to so construct the valves as to lap, that at no position of the engine-cranks will the entrance-ports of both cylinders be covered, for, if so made, it will be obvious to steam-engineers that the engine might be stopped where the entrance-ports of both cylinders would be covered, and the links at their extreme throw or position, so that, instead of being able to start the engine in the direction required, it would first have to be reversed, and afterward set in motion in the desired direction.

In fig. 1, one of these cylinders is represented by *a*, its steam and valve-chest by *b*, the valve-rod by *c*, which is worked by the Stephenson link *d*, operated by two eccentrics on the main shaft *e*, by rods *ff*.

By means of the links, one of which and the connections mentioned are applied to each cylinder of the connected double engine, the direction of rotation of the main shaft may be reversed, and the point of cut-off varied, in accordance with the position of the link, the valves worked thereby being made with suitable lap and lead, and most generally of the short D variety; all of which is too familiarly known to steam-engineers to need particular description here.

When the link is brought to the position shown in full lines in fig. 2, the valve is brought to position, and is opened, to admit steam to run the engine, so as to turn the shaft in one direction, and, when the link is brought to the position shown by dotted lines in the same figure, then the valve is so opened as to run the engine, so as to turn the shaft in the opposite direction; and, when the link is adjusted so that its connection with the valve-stem is midway between the points at which the link is suspended from the eccen-

tric-rod *f*, then the valve shuts off steam from the cylinder, and the engine stops.

When the link is in either of the first two positions just before named, steam follows the piston through or nearly through its entire stroke; and, when in position between either of said two positions and the point midway between them, the steam is cut off more or less, according as the position approximates the center point, where it is entirely cut off.

To move the link from one extreme position to the other, to reverse the engine, sheaves *g g* are arranged so that one part of an endless band, *h*, preferably a wire, cord, or rope, will always be within the reach of the conductor.

The lower sheave is connected to the Stephenson link *d* by the rod *i*, so that it will be obvious how the conductor can, by a pull in one or the other direction upon rope *h*, shift the link *d* to either of its extreme positions, and how, by merely grasping the rope *h*, so as to cause it to move at the same speed with the car or platform *k*, the link will be shifted to the midway point between its extreme positions, where the steam being shut off, both the engine and car will stop.

Now, to cause the link to move automatically from either extreme position to a point between such position and the central one, I place on the opposite parts of the cord *h* weights *l l* and tappets *m m*, the weights and tappets being preferably made tubular, so as to embrace the cord, and the tappets being provided with set-screws and gibbs or other appliances, whereby they can be adjusted and fixed on the cord.

Shelves or other suitable supports, *o*, are arranged so as to support the weights *l*, the parts of the cords passing through holes or slots in the supports.

It will be seen, that when the conductor pulls the cord, so as to swing link *d* to either extreme position, he will bring one or the other tappet *m* into contact with one or the other of weights *l*, and will raise said weight off from its support. The weight will then descend till it rests upon its support, and, by turning the sheave *g*, which is connected to link *d*, will cause said link to assume the position where it will give the amount of cut-off required.

The distances at which the tappets *m* are adjusted

on the rope *h* from the weights will determine where, between either extreme position of the link and its central position, either weight will set the link, and, consequently, determines the point of cut-off.

In an unbalanced elevator, much more steam is required to lift the car than to lower it. Consequently, in such case, the tappets are usually preferably set so as to supply more steam to the cylinders when raising the car than when lowering it.

Under some circumstances, in lowering a car, it will be sufficient to supply the cylinders with little more than enough steam to lubricate them.

The link *d* shown in the drawings is hung like a pendulum, and, consequently, requires but little exertion of power on the part of the conductor to move it.

When it is necessary to arrange the link differently, its weight may be counterbalanced, so that it may be moved about as easily as a pendulum-link.

It will be observed, that while the weights are falling, the distances which the steam follows the piston constantly lessen, by reason of the changing position of the link, until the weights rest on their supports, when the cut-off points become constant.

The links of both cylinders are to be connected as in locomotives and other engines employing two cylinders, so that both links will be operated by the same means.

In fig. 1, the link is shown as set to give steam in hoisting, and in fig. 3 in lowering.

In fig. 2, the full lines show the link set to start to elevate, and in dotted lines to start to lower.

I claim the combination with an elevator worked by an engine so that the car or platform is started, moved, stopped, or reversed by starting, moving, stopping, or reversing the engine, of instrumentalities which are manipulated from said car or platform to start, move, stop, or reverse both the car or platform and the engine, when said instrumentalities automatically operate to change the distance or distances which the steam follows the engine-piston or pistons.

MARTIN L. WYMAN.
